UNITED STATES PATENT OFFICE

123,290

DESIGN FOR A COMMERCIAL VACUUM CLEANER

Joseph J. Colling, Pittsburgh, Pa.

Application June 5, 1940, Serial No. 92,825

Term of patent 14 years

To all whom it may concern:

Be it known that I, Joseph J. Colling, a citizen of the United States, residing at Pittsburgh, in the county of Allegheny and State of Pennsylvania, have invented a new, original, and ornamental Design for Commercial Vacuum Cleaners, of which the following is a specification, reference being had to the accompanying drawing, forming part thereof.

Figure 1 is a perspective side view of a commercial vacuum cleaner. Figure 2 is a top view of Figure 1 showing my new design.

I claim:

The ornamental design for a commercial vacuum cleaner, as shown.

JOSEPH J. COLLING.
